UNITED STATES PATENT OFFICE.

HILMA C. A. BOWMAN, OF MINNEAPOLIS, MINNESOTA.

DESIGN FOR A FLAG.

61,082.

Specification for Design.

Patented June 20, 1922.

Application filed August 6, 1917. Serial No. 184,757. Term of patent 3½ years.

To all whom it may concern:

Be it known that I, HILMA C. A. BOWMAN, a citizen of the United States, residing at Minneapolis, in the county of Hennepin and State of Minnesota, have invented a new, original, and ornamental Design for a Flag, of which the following is a specification, reference being had to the accompanying drawing, forming part thereof.

The invention consists of a flag having the rainbow emblem which comprises the colors red, orange, yellow, green, blue, indigo and violet.

The figure is a plan view of a flag, showing my new design.

I claim:

The ornamental design for a flag, as herein described and shown.

HILMA C. A. BOWMAN.
